Application January 23, 1936, Serial No. 60,415
In Germany January 28, 1935

15 Claims. (Cl. 179—17)

The invention relates to remote communication systems more especially telephone systems in which incoming lines in various traffic directions are connected over a common connecting line with a plurality of connecting devices and in which each traffic direction or each group of traffic directions is associated in the exchange with a particular connecting device.

The characterizing of the incoming traffic direction and the selection of the connecting device associated with this traffic direction is accomplished by earthing one or other of the leads of the connecting line which is common to all the traffic directions. In the known arrangements of this kind difficulties are involved in that the earth determining the connecting device to be used in the exchange and hence also the incoming traffic direction operates on subsequently arranged connecting devices and causes undesired switching operations in these such as "toll knock down".

According to the invention the foregoing difficulties are avoided in that switching devices are provided at the junction point connecting the common connecting line with the connecting devices, which, after the connecting path has been seized, delay the switching through of the speaking line in the particular outgoing traffic direction to be used until after the disconnection from the calling line of the earth which determines the incoming and outgoing traffic direction.

In order not to have to provide specially equipped connecting devices or special means of access to the groups of connecting devices (by call finders) for this mode of operation which differs from the normal (individual subscribers), it has already been proposed to arrange special repeaters and junctions before the normal connecting devices or the approaches thereto, which in dependence upon the characteristic of the incoming traffic direction would set in operation a connecting device corresponding to this traffic direction for the purpose of establishing the connecting path. Difficulties arise in the operation of the foregoing devices on account of the desirability of avoiding any appreciable modification of the normal connecting device, such as the pre-selector or call finder when operating with connecting lines common to several lines or groups of lines. Influencing of the calling and controlling devices has previously only been accomplished by relays connected permanently to the speaking line but this introduces difficulties both in the further establishment of connecting

paths and also in the occurrence and transmission of switching operations during the existence of a call.

The present invention has as one of its objects the arrangement of a connecting path which will allow the calling and controlling devices to be influenced without permitting the devices of the junction to exert any disturbing influence during the final setting up of the call or while the call is in progress, or while it is being released. This is accomplished by providing a relay which characterizes the incoming and outgoing traffic direction and governs the device controlling the junction, after determining the traffic direction appropriate to the call (e. g. after the completion of the pre-selection), the relay is rendered ineffective by a switching means which is placed transitorily under the influence of following switching devices.

In these systems faults may occur in the setting up of a call if, when a call has been initiated by one of the subscribers, the other subscriber happens to take up his receiver before his line has been rendered inoperative. The chance of this happening is small; it is, however, considerably increased if, when setting up such a call, the bell of the station which is not calling is operated through the discharging of the condenser connected with the bell on account of the reversal of the current direction in the one lead of the party line. Such faults are avoided according to the invention in that the reversal of the current direction taking place over the party line is effected in stages so as to avoid influencing the bell of the station which is not calling before this station is disconnected or locked out.

In the embodiment of the invention the special line may constitute a so-called "two-party" line in which a common connecting line is led to a switching point to which the two subscribers are connected. The invention is, however, not limited to an arrangement of this sort. It is easily possible to connect up more than two subscribers' lines at the switching point, or alternatively, instead of subscribers' lines, connecting lines, party lines or the like may be connected up.

The drawings comprising Figs. 1, 2, and 3, show by means of the usual circuit diagrams several embodiments and modifications of the various features of the invention.

In the embodiment of Fig. 1 two subscribers' stations $TSt1$ and $TSt2$ are shown whose lines are connected together and to the common connecting line VL at the switching point $USt1$. This connecting line leads via the switching point

US₂ to the exchange devices where an individual pre-selecting device such as pre-selector VW₁ is provided for each subscriber of the two-party line. Communication between the two subscribers of the party line is not possible.

- The mode of operation of Fig. 1 is as follows: If a subscriber, for example the subscriber at station TSt₁, wishes to set up a call, he takes up his receiver and thereby closes a circuit for relay R₁ at the switching point US₂: earth, battery, winding of relay R₁, contacts 1t₁, 2t₂, a-lead of the connecting line, winding I of relay U₁, contact 22u₂, subscriber's station TSt₁, contact 21u₂, winding II of relay U₁, contact 3u₁, earth. Relay U₁ in this circuit does not energize. Relay R₁ energizes, however, and at its contact 4r₁ closes a circuit for the auxiliary relay H₁. This energizes and over its contact 5h₁ gives the starting impulse to the pre-selector VW₁: earth, battery, resistance W₁, contact 5h₁, b-lead to the pre-selector VW₁, contact 6t₁, relay R, earth. The pre-selector is set in operation and on leaving the normal position breaks the holding circuit for relay T₁ which is energized when the system is at normal. Relay T₁ releases and by opening contact 7t₁ breaks the starting circuit for subscriber TSt₂ and by closing contact 8t₁ prepares the connection of the connecting line to the exchange devices.
- When the pre-selector steps to a free group selector relay T in the pre-selector energizes in the known way and switches the line through to the pre-selector at its contacts 9t and 10t. A circuit is thereby established for winding II of relay R₁ the short-circuit for which was removed by the opening of contact 12r₁ on the energizing of relay R₁: earth, battery in the group selector, relay A in the group selector, a-lead, contact 9t, winding II of relay R₁, contact 11r₁, resistance W₂, earth. The winding II of relay R₁ opposes winding I so that when the former energizes the relay R₁, which was previously held energized over resistance W₂ and contacts 13r₁ and 14t₁, releases. Contacts 12r₁ and 15t₁ are thereupon closed and battery from the group selector is thereby connected to the switching point US₁ over the a-lead of the connecting line. At the switching position US₁ relay U₁ energizes and closes its contact 16u₁. After earth has been disconnected from it at the switching point US₁ relay U₁ holds up over earth at the switching point US₂ by way of the circuit: earth, contact 17r₁, resistance W₄, contacts 18h₁, 8t₁, b-lead of the connecting line, contact 16u₁, winding II of relay U₁, contact 21u₂, winding I of relay U₁, a-lead of the pre-selector VW₁, a-lead to the group selector, battery, earth.

As a result of the release of relay R₁ the circuit for relay H₁ is broken and this relay makes a delayed release on account of its short-circuiting winding. Contact 19h₁ is accordingly closed after a certain time, while contacts 5h₁ and 18h₁ are opened. The b-lead is now switched through to the group selector over contact 19h₁. This slow acting device ensures that the switching over relay U₁ at the switching point US₁ has duly switched through the b-lead of the subscriber's line. This prevents the criterion for "toll knock down" (relay A energized, relay B de-energized) from being given, since — potential is connected to the b-lead of the line leading to the pre-selector until the disconnection from earth and the switching through of the b-lead has taken place at the switching over point US₁. The calling subscriber's connecting path to the

group selector is now established so that dialling can commence. The subsequent operations are the same as those for a normal subscriber's connection.

If when starting up a call the pre-selector VW₁ does not find a free group selector it steps to the 11th contact. Relay R in the pre-selector is accordingly energized again: earth, battery, resistance W₁, contacts 5h₁, 6t₁, relay R, earth. Relay T in the pre-selector energizes over contact 20r and closes its contacts 9t and 10t, so that a circuit is established for winding II of relay R₁: earth, battery, resistance W₆, rotary wiper of pre-selector VW₁ on contact 11, contact 9t, winding II of relay R₁, contact 11r₁, resistance W₂, earth. Relay R₁ releases in the manner already described when subjected to the influence of the opposing winding II and causes the speaking line to be switched through to the pre-selector in the same manner as when testing on a free group selector. The engaged signal is connected to the 11th step of the pre-selector in the known manner, and is therefore transmitted to the subscriber. The subscriber thereupon replaces his receiver thereby causing the release of the connecting path set up. The pre-selector returns to normal in which position the relay T₁ at the switching point US₂ again energizes thereby closing contact 1t₁ and 7t₁. The system is now restored to normal.

The same operations take place when a call is initiated by the subscriber of the station TSt₂ provided that the subscriber of station TSt₁ is not holding a call at the time. If this is the case the contacts 23u₁ and 24u₁ are open so that the line of the subscriber at station US₂ is doubly disconnected, and manipulation of the switch hook or dial at this station is without effect. Since however, relay U₁ or U₂ does not energize until the pre-selector has been set in the exchange, devices are provided at the switching point US₂ which prevent the bell at the subscriber's station TSt₂ from operating when the potential on the b-lead of the connecting line, which in the normal condition of the system is negative, is changed to earth potential. The devices are so arranged that on the energizing of relay H₁ the earth potential is connected up over the very high resistance W₅ to the b-lead of the connecting line so that the condenser associated with the bell of the subscriber's station TSt₂ can gradually discharge while the direct connection of earth over contact 17r₁ on the release of relay R₁ does not take place until the discharge of the condenser has already proceeded so far that it is no longer possible for the bell in the second subscriber's station to respond. This arrangement is particularly important since a removal of the receiver at the second subscriber's station, occasioned by a brief operation of the bell, would produce undesirable disturbances in the establishment of the first subscriber's call.

Devices are provided at the switching over point US₂ which prevent incoming exchange calls from seizing the two-party line when one of the subscribers is engaged in a call. Thus, for example, when the subscriber at station TSt₂ is engaged in a call contact 28r₂ is closed as a result of the energizing of relay R₂ and accordingly the high resistance winding I of relay T₁ is short-circuited, while when the subscriber of station TSt₁ is engaged in a call contact 27t₂ is closed on account of the energizing of relay T₁ and this similarly short-circuits the high resist-

ance winding I of relay T₁. In either case seizure of the line after testing on the c-lead, which is connected to earth over the low resistance winding II of relay T₁, is not possible.

5 According to the second embodiment, Fig. 2, the controlling means (T₁ and T₂) at the switching over point USt₂, are not energized in a circuit which is in effect when the system is at normal as is the case in Fig. 1, but are first operated 10 when a call is initiated. The switching operations which take place in Fig. 2 are as follows: When the subscriber at station TSt₁, for example, takes up his receiver the following circuit is completed: earth, battery, winding I of relay R₁, contacts 1t₁, 2t₂, a-lead of the connecting line VL, winding I of relay U₁, contact 3u₂, line to station TSt₁, contact 4u₂, winding II of relay U₁, contact 5u₁, earth. In this circuit relay R₁ energizes but not relay U₁. The former relay 15 switches over its contacts thus connecting —potential over resistance W₁ and contact 6r₁ to the pre-selector VW₁ by way of the b-lead. The following circuit is therefore set up for relay R₁ in the pre-selector: earth, relay R, contact 1t, b-lead contact 6r₁, resistance W₁, battery, earth. 20 The pre-selector is set in operation. At contact 8r₁ a circuit is prepared for the high resistance winding I of relay T₁.

25 When the pre-selector VW₁ tests on a free group selector relay T in the pre-selector energizes in the known manner over the c-lead and brings the pre-selector to rest. Contacts 9t and 10t at the pre-selector are closed. A circuit is accordingly set up for relay T₁ at the switching over point USt₂: earth, battery, relay A in the group selector, a-lead, contact 9t, a-lead, contact 8r₁, winding I of relay T₁, earth. Relay T₁ energizes and establishes a locking circuit over contact 11t₁: earth, battery, winding II of relay T₁, resistance W₃, contact 11t₁, earth. At the same time contacts 12t₁ and 1t₁ are opened and contacts 13t₁ and 14t₁ closed. The —potential of the group selector is accordingly connected to the switching over point USt₁ by way of the 30 a-lead of the connecting line so that relay U₁ energizes over the circuit: earth, battery, relay A in the group selector, a-lead, contact 9t, a-lead, contacts 13t₁, 2t₂, a-lead of the connecting line, winding I of relay U₁, contact 3u₂, line to station TSt₁, contact 4u₂, winding II of relay U₁, contact 5u₁, earth. Relay U₁ operates and closes contact 15u₁. At the same time both leads of the second subscriber's station are disconnected by the opening of contacts 16u₁ and 17u₁. After 35 the closing of contact 15u₁ relay U₁ holds up over: earth, contact 18r₁, resistance W₄, contact 14t₁, b-lead of the connecting line, contact 15u₁.

40 The energizing of relay T₁ at the switching over point USt₂ also has the effect of disconnecting relay R₁. This relay, however, makes a delayed release on account of its short-circuiting winding II so that a certain period elapses before contact 45 6r₁ opens. This period is sufficiently long to ensure the energizing of relay U₁ at the switching over point USt₁ and the switching through of the b-lead of the connecting line. When contact 19r₁ closes, relay R₁ having completely released, the loop to the group selector is securely closed at the switching over point USt₁ so that the false "toll knock down" signal (relay A energized, relay B deenergized) cannot be given in the group selector. Furthermore, through the 50 release of relay R₁ winding I of relay T₁ is dis-

connected from the a-lead and resistance W₄ from the b-lead by the opening of contacts 8r₁ and 18r₁, respectively. Relay T₁ holds up, however, throughout the duration of the call in a local circuit over its winding II. Relay T₁ thus 5 serves to prevent incoming calls seizing the two-party line when the latter is engaged.

On the release of the connection relay T₁ releases since when the pre-selector returns to normal the locking winding of relay T₁ is connected 10 in parallel to relay T of the pre-selector. Relay T₁ therefore deenergizes, and closes contacts 1t₁ and 12t₁ so that the system is once more restored to normal.

15 In the third modification and embodiment of the invention as shown in Fig. 3, the preselecting switches of the exchange devices are constructed as call finders, and this involves certain alterations and simplifications (at the switch-over point USt₂) as compared with the arrangement employing preselectors as shown in the first two 20 embodiments.

The switching operations of Fig. 3 are as follows: When, for example, the subscriber at station TSt₁ takes up his receiver relay R₁ energizes at the switch-over point USt₂ in the following circuit: earth, battery, relay R₁, contacts 1t₁, 2t₂, a-lead of the connecting line VL, relay U₁, winding I, contact 3u₂, line to subscriber's station TSt₁, contact 4u₂, winding II of relay U₁, contact 5u₁, earth. Relay U₁ does not energize in series with relay R₁. Relay R₁, however, energizes and closes its contacts. Resistance W₁ is connected to the b-lead of the line to the call 30 finder over contact 6r₁ while over contact 7r₁ 35 the starting impulse is given to the call finder over the a-lead of the speaking line: earth, battery, relay R winding I in the call finder, contact 9t, a-lead, contact 8r₁ at the switch-over point USt₂, resistance W₂, contact 7r₁, earth. Relay R energizes and causes the call finder to step 40 round in the known way. The testing circuit for relay T in the call finder is prepared over the contacts 10r and 11r. When the call finder tests on the calling line relay T energizes, brings 45 the call finder to rest in the known way and closes contacts 13t and 14t, so that now the potentials which are connected to the speaking line in the group selector which has been seized are 50 connected to the two leads of the speaking line leading from the call finder to the switching over point USt₂.

When the call finder tests on the calling line, 55 relay T₁ is connected in parallel to the low resistance connected to the c-lead of the call finder so that it can no longer remain energized. Relay T₁ accordingly releases, opens contact 1t₁ and closes contact 15t₁ so that the a-lead of the speaking line is switched through to the calling station. Relay U₁ at the switching over point USt₁ thereupon energizes: earth, contact 5u₁, winding II of relay U₁, contact 4u₂, line to the subscriber's station TSt₁, contact 3u₂, relay U winding I, a-lead of the connecting line, contact 2t₂, 15t₁, a-lead of the speaking line passing over the call finder AS₁ to the group selector, battery, and earth. Relay U₁ by closing contact 16u₁ causes the b-lead to be switched through at the switching over point USt₁. Relay U₁ thereupon holds up, after the disconnection of 60 the earth at the switching over point USt₁, over the b-lead of the connecting line, contacts 17t₁, 18r₁, resistance W₃, earth (at the switching-over point USt₂). On account of the opening 65 of contact 1t₁ when the call finder tests on the 70 75

calling line, the circuit for relay R_1 was broken. This relay makes a delayed release on account of its short-circuiting winding, so that the contacts $6r_1$ and $18r_1$ only open after a certain lapse of time. This interval is sufficient to enable relay U_1 at the switch-over point USt_1 to energize fully and for the switching through of the b -lead of the speaking line to occur at the switching-over point. When then on the release of relay R_1 contact $19r_1$ is closed the loop between the speaking leads of the connecting path set up to the group selector is completed. Accordingly the disturbances which may occur if relay A in the group selector is energized over the a -lead of the connecting line while relay B is not yet energized over the b -lead of the connecting line are avoided. These switching conditions of the two relays in the group selector (A energized, B de-energized) form the criterion for "toll knock down". The same signal would also be given if on the release of relay T_1 both leads of the speaking line were immediately switched through at the switching over point USt_2 since some time elapses before the loop is completed over contact $16u_1$ after relay U_1 has energized over the a -lead.

In the embodiment of Fig. 3 just as in the arrangement according to Fig. 1 a reversal of the current direction takes place over one of the leads of the connecting line. In this case, however, alteration of the current in stages is not absolutely necessary since when using call finders the reversal of the current direction only takes place when the call finder has been set on the calling line. Reversal of the current direction, therefore, occurs practically simultaneously with the energizing of the relay U_1 of the calling station so that the disconnection of the other subscriber takes place immediately and any possible removal of the receiver at this subscriber's station provoked by the short operation of the bell remains inoperative. It is, however, possible, of course, to arrange the reversal of the current in stages in this arrangement also. In addition, in Fig. 3 arrangements are provided at the switching over point USt_2 which prevent incoming calls from testing on the two-party line when one of the subscribers of this line is already engaged. Thus, if for example, subscriber TSt_2 is speaking either relay R_2 is energized and contact $20r_2$ is closed when a call is initiated or relay T_2 is de-energized and contact $21t_2$ is accordingly closed, i. e. in both cases the high resistance winding I of relay T_1 is short-circuited so that a final selector cannot be set on this line.

55 What is claimed is:

1. In a telephone system, a plurality of telephone lines, a plurality of connecting switches, a common connecting line individual to said switches over which said telephone lines have access to said switches to extend connections therefrom to other lines, means responsive to a call from one of said telephone lines for taking said common connecting line into use, associating the telephone line with either one of said switches and operating the associated switch to extend the connection from said line, and means for delaying the switching through of the telephone line to the connecting switch until after it is determined that the call is an incoming or an outgoing one.

2. In a telephone system, a plurality of telephone lines, a plurality of connecting switches, a common connecting line individual to said lines and said switches over which said telephone lines have access to said switches, means responsive to

5 a call from one of said telephone lines for taking said common connecting line into use to the exclusion of the other telephone line, associating the calling telephone line with either one of said switches and operating the associated switch to extend the connection from said telephone line, means for determining whether said call is an outgoing one or an incoming one, and means for delaying the extension of said calling telephone line through the connected switch until 10 said call determining means has been disconnected from the calling line.

3. In a telephone system, a pair of telephones connected at a common point to a connecting line, connecting switches accessible to said connecting line, means responsive to a call from one of said telephones for taking said connecting line into use and for disconnecting the other of said telephones to prevent its taking said common line into use, means also responsive to said call for seizing one of said connecting switches to extend the call, means for determining whether said call is an incoming or an outgoing one, said means comprising the grounding of said calling line, and means for delaying the extension of said call through said switches until said ground has been disconnected from said calling line.

4. In a telephone system as claimed in claim 3, means individual to each telephone line for disconnecting the other telephone line from use while said first line is calling and also for determining whether the call is an incoming or an outgoing one, said means operative only when the calling line has been switched through by the connecting switch.

5. In a telephone system, a pair of telephone lines connected to a common line, a pair of switches one for each of said lines accessible to said common line, means responsive to a call from one of said lines for taking said common line into use and for engaging said common line with one of said switches, means responsive to the extension of the call through said switch for reversing the flow of current over said line, other means responsive to the extension of said call for disconnecting the other of said telephones from the use of said common line, and means responsive to the reversal of current flow over said common line for preventing the operation of the ringer of the other telephone before said telephone is disconnected from the common line.

6. In a telephone system as claimed in claim 5, in which the reversal of current flow at the common line connects a high resistance to ground from one side of the line in order to gradually discharge the condenser associated with the ringer of the said other line and prevent the operation of the ringer before the said line is disconnected.

7. In a telephone system, a plurality of telephone lines connected to a common line, a plurality of connecting switches to which said common line has access, switching means at the junction of said common line and said connecting switches, a line relay in each telephone line controlling the incoming and outgoing direction of calls on said telephone line and also controlling said junction switching means, means responsive to an outgoing call from one of said telephone lines for operating the associated line relay over said common line to operate the junction switching means and connect the calling line to one of said connecting switches, and means responsive to the extension of the call through the said con- 75

necting switch for releasing said line relay from in circuit of said line.

8. In a telephone system, a pair of telephones connected to a common line, a pair of connecting switches accessible to said line, a switching relay at the junction of said common line and said switches, a line relay for each line, means responsive to a call from one line for operating its associated line relay to connect said calling line to one of said switches and to operate said switching relay to connect the common line to the calling line, means responsive to the extension of the calling line through the operated switch to release the line relay from the line, and means also responsive to the extension of the calling line for disconnecting the other telephone from the common line.

9. In a telephone system, as claimed in claim 7, a selector switch accessible to said connecting switches and selectable thereby to extend the calling line, and means controlled over the line by a selected idle selector switch for controlling the operation of the line relay in the calling line.

10. In a telephone system as claimed in claim 7, in which the line relay is provided with differentially arranged windings, one of which is energized to operate the relay responsive to an outgoing call to extend the call, while the other winding is energized to release the relay responsive to the extension of the call through the connecting switch.

11. In a telephone system as claimed in claim 7 in which the line relay is provided with differentially arranged windings one of which is energized to operate the relay responsive to an outgoing call from the associated line, while the other winding is energized to release the relay responsive to the extension of the call through the connecting switch, and means on said relay responsive to its release for disconnecting said second winding from the line.

12. In a telephone system, as claimed in claim 7, in which the line relay of the calling line is included in the connecting path to each connecting switch and operates the junction switching means to disconnect the line relay of the other telephone line, said switching means comprising a relay for determining the incoming or outgoing direction of the call.

13. In a telephone system, a common junction line, a pair of telephone lines branched from one

end of said common line, a pair of junction lines branched from the other end of said common line, a selecting switch individual to each of the said junction lines and operable thereover, means in each junction line responsive to a call from one of said telephone lines for extending the call over said common line to one of the junction lines to the associated selecting switch, and means responsive to the extension of the call for disconnecting the other of said junction lines from the common line and for disconnecting the other of said telephone lines from the common line.

14. In a telephone system, a common junction line, a pair of telephone lines branched from one end of said common junction line, a pair of junction lines branched from the other end of said common line, a selecting switch in which each of said junction lines terminate, means in each junction line responsive to a call from one of said telephone lines for extending the call over said common line to one of the junction lines and its associated switch, a line relay for each telephone line, the line relay of one of said lines responsive to the extension of a call from said line for disconnecting the other telephone line from the common line, and a switching relay for each junction line responsive to a call from one line to disconnect the other junction line from the common line.

15. In a telephone system, a common junction line, a pair of telephone lines branched from one end of said telephone line, a pair of junction lines branched from the other end of said common line, a selecting switch in which each of said junction lines terminate, means in each junction line controlled over one side of the common line in response to a call from one of said telephone lines for extending the call over said common line to one of the junction lines to the associated selecting switch, means responsive to the extension of a call for disconnecting the other of said junction lines from the common line for disconnecting the other of said telephone lines from the common line, a call from the other side said common line to the other junction line and selecting switch, and means responsive to the extension of a call for switching through both sides of the common line to the calling junction line.

FRITZ WOLF. 50
